UNITED STATES PATENT OFFICE.

JOHN STOVEKEN, OF CRIPPLECREEK, AND LEO STOVEKEN, OF FLORENCE, COLORADO.

FILTER-PRESS.

SPECIFICATION forming part of Letters Patent No. 729,807, dated June 2, 1903.

Application filed November 21, 1902, Serial No. 132,228. (No model.)

To all whom it may concern:

Be it known that we, JOHN STOVEKEN, residing at Cripplecreek, in the county of Teller, and LEO STOVEKEN, residing at Florence, in the county of Fremont, State of Colorado, citizens of the United States, have invented new and useful Improvements in Filter-Presses, of which the following is a specification.

Our invention relates to filter-presses—*i. e.*, 10 apparatus for separating liquids from solids or semisolids; and it has for its object to provide a simple and inexpensive filter-press adapted to be quickly and easily charged with substance to be filtered and as quickly and 15 easily discharged of the residue subsequent to an operation and one which is a more efficient drier of material than filter-presses extant, and hence is well fitted for use in localities where water is scarce.

20 The invention will be fully understood from the following description and claims when taken in connection with the accompanying drawings, in which—

Figure 1 is a vertical longitudinal central 25 section of a filter-press constructed in accordance with our invention; Fig. 2, an enlarged detail perspective view, partly broken away, of one of the bags comprised in the press; Fig. 3, a side elevation of the press; Fig. 4, a trans- 30 verse section taken in the plane indicated by line 4 4 of Fig. 1; Fig. 5, an end elevation of the press; Fig. 6, a detail horizontal section taken in the plane indicated by the line 6 6 of Fig. 1, and Fig. 7 a detail transverse section taken in the plane indicated by line 7 7 of Fig. 1.

Similar letters of reference designate corresponding parts in all of the several views of the drawings, referring to which—

40 A is the main frame of our improved filter-press, which is preferably of metal and has a head *a* at one end; B, a cylinder fixed to the head *a* and provided with means for admitting and exhausting compressed air or 45 other fluid-pressure; C, a piston movable in the cylinder B and having a rod *b*; D D, four (more or less) foraminated plates, preferably of metal, fixedly connected to longitudinal bars *c* of the frame A; E E, four (more or 50 less) foraminated plates, preferably of metal,

mounted on the frame-bars *c* and each movable toward and from one of the fixed plates D; F F, bags of filter-cloth, canvas, or other suitable material, each of which is arranged between a fixed plate D and a complementary 55 movable plate E and is provided at its lower end, Fig. 2, with a bail-shaped gate *d*, preferably of metal, which is connected to the filter cloth or canvas and is pivoted at its upper end to a bail-shaped frame *e*, also connected to the filter cloth or canvas; G, a longitudinal conduit for the material to be filtered arranged above the bags F; H H, hose-pipes interposed between and connecting the bags F and the conduit G; I I, pinch-cocks 60 fulcrumed at *f* adjacent to the hose-pipes and adapted to pinch the said pipes against sleeves or abutments *g*, and thereby close the pipes and cut off the supply of material to the bags F; J, Figs. 1, 3, and 5, a longitudinal endwise- 65 movable rod connected to the several cocks I and provided in order to enable an attendant standing at one end of the apparatus to simultaneously open or close all of the cocks; K K, endwise-movable longitudinal bars disposed 70 at opposite sides of the apparatus and connected to the movable plates E; L, a cross-bar connecting the bars K and the rod *b* of piston C; M M, endwise-movable longitudinal bars connected by pivoted links *h*, Fig. 80 2, or other suitable means with the gates *d* of the several bags F and having racks *i*, and N a transverse shaft journaled in suitable bearings adjacent to the plate *a* and having pinions *j* intermeshed with the racks *i* of bars 85 M and also having a hand-wheel *k*.

The operation of our improved filter-press is as follows: The material to be filtered is supplied to the several bags F through the conduit G and the hose-pipes H and while 90 the plates E are in the positions shown with respect to the stationary plates D, after which the rod J is moved in the direction indicated by arrow, Fig. 1, so as to cause the cocks I to pinch the hose-pipes H against the abutments *g* and close communication between the bags F and the conduit G. Then fluid-pressure is let into the cylinder B, so as to move the piston C and the several plates E, connected therewith, in the direction indi- 95 100

cated by arrow in Fig. 1, when the material in the bags F will be subjected to pressure between the plates E and D and all of the liquids in the material will be separated from the solids and forced through the filter cloth or canvas of the bags. From this it follows that our improved machine is highly efficient in recovering all of the liquid or solution from the material, and hence is adapted to be used 10 to advantage in localities where water is not plentiful.

Subsequent to the described operation of separating the liquid in the material from the solids the plates E are returned to the positions shown in Fig. 1, preferably by letting fluid-pressure into the cylinder B, so as to move the piston C in the direction opposite to that indicated by arrow; after which the bars M are moved, through the medium of the 20 shaft N, in the direction opposite to that indicated by arrow to open the gates d of the several bags F and effect the discharge of the solids or residue from said bags. With this done the gates d are closed by moving the bars M in the direction indicated by arrow. The bar J is moved in the direction opposite to that indicated by arrow to reëstablish communication between the conduit G and bags F and effect a refilling of the latter, and the 25 30 operation described is repeated.

It will be appreciated from the foregoing that the discharge of the solids or residue from the bags F and the subsequent closing of the bags and reëstablishment of communication between the same and the conduit G entail but a minimum amount of delay and but little effort on the part of the attendant, which is an important advantage.

We have entered into a detailed description 40 of the construction and relative arrangement of the parts embodied in the present and preferred embodiment of our invention in order to impart a full, clear, and exact understanding of the same. We do not desire, 45 however, to be understood as confining ourselves to such specific construction and arrangement of parts, as such changes or modifications may be made in practice as fairly fall within the scope of our invention as claimed.

50 Having described our invention, what we claim, and desire to secure by Letters Patent, is—

1. In a filter-press, the combination of a bag having an inlet for material to be pressed, and 55 also having a discharge-gate, means for pressing the bag, and means for holding the gate closed while the bag is being pressed.

2. In a filter-press, the combination of a bag having a bail-shaped frame and a bail-shaped 60 gate at its lower end; the gate being pivoted to the frame, means for pressing the bag, and means for holding the gate closed while the bag is being pressed.

65 3. In a filter-press, the combination of a bag having a gate at its lower end, a conduit connected with the upper portion of the bag, means for pressing the bag, means for clos-

ing the conduit while the bag is being pressed, and means for holding the gate closed during said pressing.

4. In a filter-press, the combination of abutments, means for moving one of the same, a bag interposed between said abutments, and having an inlet for material to be pressed, and also having a discharge-gate at its lower end, and means for holding the gate closed while the bag is being pressed between the abutments. 75

5. In a filter-press, the combination of a fixed abutment, a movable abutment, means for moving the latter, a bag interposed between said abutments, and having a gate at its lower end, a conduit connected with the upper portion of the bag, means for closing said conduit while the bag is being pressed 85 between the abutments, and means for holding the gate closed during said pressing.

6. In a filter-press, the combination of a fixed abutment, a movable abutment, means for moving the latter, a supply-conduit arranged above the abutment, a bag interposed between the abutments, and having a gate at its lower end, means for holding said gate closed while the bag is being pressed between the abutments, a hose-pipe interposed between the supply-conduit and the bag, and a 95 pinch-cock arranged to engage said hose-pipe.

7. In a filter-press, the combination of a bag, connected with a source of material-supply, and having a discharge-opening, separate 100 from said connection, and means for closing said opening, means for pressing the bag, and means for controlling communication between the source of material-supply and the bag.

8. In a filter-press, the combination of a main frame, a foraminated plate fixed thereto, a foraminated plate movable in the frame toward and from the fixed plate, means for moving the movable plate, a bag interposed 110 between the said plates, and having an opening at its lower end, and means for closing the same, a material-supply conduit disposed above the bag, a hose-pipe interposed between the supply-conduit and the bag, and means 115 controlling said hose-pipe.

9. In a filter-press, the combination of a main frame, a plurality of plates fixed thereto, a plurality of complementary plates movable in the frame, bags interposed between the fixed plates and the complementary movable plates, and means connected with the several 120 movable plates for simultaneously moving the same.

10. In a filter-press, the combination of a main frame, a plurality of plates fixed thereto, a plurality of complementary plates movable in the frame, means for moving the latter plates, bags interposed between the fixed plates and the complementary movable 130 plates, and having gates at their lower ends, and means connected with said gates, whereby the lower ends of the several bags may be simultaneously opened and closed.

11. In a filter-press, the combination of a main frame, a plurality of plates fixed thereto, a plurality of complementary plates movable in the frame, bags interposed between the 5 fixed plates and the complementary movable plates, and having gates at their lower ends, means for simultaneously moving the movable plates toward and from the fixed plates, and means for simultaneously opening and 10 closing the gates of the several bags.

12. In a filter-press, the combination of a plurality of bags having gates at their lower ends, means for pressing the said bags, and means connected with the gates of the 15 several bags, whereby said gates may be simultaneously opened and closed.

13. In a filter-press, the combination of a material source of supply, a plurality of bags connected with said source of supply, and 20 having gates at their lower ends, means for simultaneously opening and closing communication between the source of supply and the bags, means for pressing the bags, and means connected with the gates of the bags, whereby 25 said gates may be simultaneously opened and closed.

14. In a filter-press, the combination of a main frame, a plurality of plates fixed in the frame, a plurality of complementary plates 30 movable in the frame, a cylinder adapted to be connected with a source of fluid-pressure supply, a piston movable in said cylinder, longitudinal bars connected to the several movable plates, a connection between said 35 bars and the piston, and bags interposed between the fixed plates and the movable plates;

each bag having an inlet for material to be pressed, and also having a discharge-opening, and means for closing said opening.

15. In a filter-press, the combination of a main frame, a material-supply conduit, a plurality of plates fixed in the frame, a plurality of complementary plates movable in the frame, a cylinder adapted to be connected with a source of fluid-pressure supply, a piston movable in said cylinder, longitudinal bars connected to the several movable plates, a cross-bar connecting said longitudinal bars and the piston, bags interposed between the fixed plates and the movable plates and having gates at their lower ends, longitudinal bars connected to said gates, and having racks, a shaft journaled in bearings on the frame, and having pinions intermeshed with said racks, hose-pipes connecting the supply- 45 conduit and the bags, pinch-cocks for closing said hose-pipes, and an endwise-movable rod connected to the several pinch-cocks.

16. In a filter-press, the combination of a bag having an inlet for material to be pressed, and also having a discharge-opening, and means for closing said opening, and means 50 for pressing the bag.

In testimony whereof we have hereunto set our hands in presence of two subscribing witnesses. 55
